UNITED STATES PATENT OFFICE

JAMES BARELS, OF CHICAGO, ILLINOIS

CARBURETOR REGULATING MECHANISM

Application filed July 7, 1928. Serial No. 291,117.

This invention relates to carburetor regulating mechanism, and its primary object is to provide simple and novel means for pre-heating air which passes through the carburetor and to regulate this preheated air.

Another object is to provide improved means, including thermo-sensitive elements, for regulating the preheated air in the carburetor according to the atmospheric temperature and according to the temperature of air and gases which pass from the exhaust to the carburetor.

Other objects and advantages will appear throughout the progress of the specification.

15 In the accompanying drawing which illustrates a selected embodiment of the invention, the views are as follows:

Fig. 1 is a detail elevation of an automobile frame and motor embodying the invention;

Fig. 2 is a top plan view of the parts shown in Fig. 1;

Fig. 3 is a detail sectional view of a portion of the intake line and the regulating valves;

20 Fig. 4 is a detail sectional view showing the means for operating the valves;

Fig. 5 is a detail enlarged view showing the thermo-sensitive means as applied to an automobile frame.

30 Referring to the drawing, 6, 6 designates the side bars of an automobile frame which support the transverse members 7, 7 carrying the motor 8. A carburetor 9 having a float chamber 10 is connected to the manifold 11, which is operatively connected to the motor in a manner well known in the art.

A pipe line 12 is connected to the motor exhaust line 13 and to the carburetor 9, for furnishing preheated air or gas to the carburetor.

40 A casing 14 is fixed to the inside of one of the side bars 6, Figs. 4 and 5, and a pair of thermo-sensitive elements 15 and 16 secured to the casing 14 as clearly shown in Fig. 4. A rod 17 is pivotally connected to the thermo-sensitive element 15 and to the arm 18 of a bell crank 19. The bell crank is pivoted to a part of the casing 14 at 20, and has an arm 21 to which the rod 22 is pivotally connected. The arm 21 of the bell crank 19 is longer than the arm 18, so that movement of the thermo-

sensitive element 15 to a slight degree causes relatively wide movement of the rod 22. It will thus be seen that lateral movement of the thermo-sensitive element will cause vertical movement of the rod 22. The thermo-sensitive element 16 operates the rod 23 in the exact same manner in which the element 15 operates the rod 22.

The pipe line 12 is enlarged at 24 and has a pair of butterfly valves 25 and 26 revolvably mounted therein, as shown in Fig. 4. The valve 25 is provided with a link 27 which is pivotally connected to the end of the rod 22, and the valve 26 has a link 28 which is pivotally connected to the rod 23. Movement of the thermo-sensitive elements 15 and 16 will therefore open and close the valves 25 and 26 according to the temperature inside of the casing 14. The carburetor 9 has an exhaust line 29 which leads to the interior of the casing 14, and the excess hot gases which pass through the carburetor are expelled through the opening 30 in the bottom of the casing 14, Fig. 5. The casing has a divisional wall 31 to provide separate compartments 32 and 33 for the elements 15 and 16, respectively. The element 16 is adapted to be controlled by the atmospheric temperature in the compartment 33, and the element 16 is controlled by the heat in the compartment 32, into which the hot gas and air from the carburetor exhaust line 29 is discharged.

When the atmospheric temperature is relatively hot it is desirable that less heat be furnished to the carburetor from the line 12, so the thermo-sensitive element 16 will operate to close the valve 26 to shut off some of the heat coming from the exhaust line 13. Also, when the motor is operating at high speed and is relatively hot it is desirable that some of the heat coming through the line 12 be shut off. If the hot gases coming out of the pipe 29 are hotter than ordinarily required, the thermo-sensitive element 15 will operate to turn the valve 25 and shut off some of the heat coming through the line 12. The thermo-sensitive metal is set to operate at certain temperatures and the rods 22 and 23 are set to operate the butterfly valves at predetermined temperatures.

Casing 14 supports the thermo-sensitive elements and some of the connecting parts, and it can be easily and quickly applied to the inside of one of the channel side bars 6 by bolts 34 or other convenient means.

5 The casing 14 may be provided with openings 35 leading to the compartment 33 to permit the temperature inside of that compartment to attain substantially atmospheric temperature.

10 The invention provides means of simple and novel construction which permit regulation of the heat to the carburetor and the casing contains most of the parts and may be 15 easily and quickly applied to any device to which it is applicable.

Changes may be made in the form, construction and arrangement of the parts without departing from the spirit of the invention or sacrificing any of its advantages, and the right is hereby reserved to make all such changes as fairly fall within the scope of the following claims:

I claim:

25 1. The combination with an automobile motor having an exhaust line and a carburetor, of a pipe line connecting the exhaust to the carburetor, for passing heated gases from the exhaust line through the carburetor, 30 means controlled by atmospheric temperature for regulating the heat passing through the pipe line, and means controlled by the temperature of the heated gases passing through the carburetor for regulating the 35 amount of heated gases coming through said pipe line.

2. The combination with an automobile motor having an exhaust line and a carburetor, of a pipe line connected to said exhaust 40 line and to said carburetor for establishing direct communication between the exhaust line and the carburetor, a pair of valves revolvably mounted in said pipe line, a thermo-sensitive element controlled by 45 atmospheric temperature for operating one of said valves, and a second thermo-sensitive element operated by the heated gases passing through the carburetor for controlling the other of said valves.

50 3. The combination with an automobile motor having an exhaust line and a carburetor, of a pipe line connected to said exhaust line and to said carburetor, a pair of valves in said pipe line, a thermo-sensitive element 55 controlled by atmospheric temperature for controlling one of said valves to control the heated gases passing through said pipe line, a second thermo-sensitive element, a carburetor exhaust line having its outlet adjacent to said 60 second thermo-sensitive element, and means connected to said second element and to the other of said valves to operate said last named valve according to the heat coming through the carburetor exhaust line.

65 4. The combination with an automobile

motor having an exhaust line and a carburetor, of a pipe line connecting said exhaust line and said carburetor, a casing connected to the automobile frame, a pair of thermo-sensitive elements arranged inside the casing, 70 a divisional wall in said casing and separating said elements, a pair of valves revolvably mounted in said pipe line, a link connected to each of said valves, a bell crank having a pair of arms and pivotally mounted in said casing, a rod connected to one of said elements and to one arm of said bell crank, a second arm connecting the link to the other arm of said bell crank, and a carburetor exhaust line discharging on one of said elements for 75 operating one of said valves, said other element being controlled by atmospheric temperature 80 and operating said other valve.
